UNITED STATES PATENT OFFICE.

CHARLES L. BRUSH, OF BOURNE, OREGON.

FOLDABLE RULE.

No. 890,599.

Specification of Letters Patent.

Patented June 16, 1908.

Application filed May 6, 1907. Serial No. 372,086.

To all whom it may concern:

Be it known that I, CHARLES L. BRUSH, a citizen of the United States, residing at Bourne, in the county of Baker and State 5 of Oregon, have invented certain new and useful Improvements in Foldable Rules, of which the following is a specification.

This invention relates to rules, and more particularly to foldable rules, and has for its 10 object to provide a rule including means for holding the sections at times in folded and at times in unfolded positions.

Another object is to provide a rule of this kind including a retaining spring of novel 15 structure facilitating the fastening thereof in position.

Other objects and advantages will be apparent from the following description, and it will be understood that changes in the specific structure shown and described may be 20 made within the scope of the claims, without departing from the spirit of the invention.

In the drawings forming a portion of this specification, and in which like numerals of 25 reference indicate similar parts in the several views, Figure 1 is a sectional view showing the rule in folded position, Fig. 2 is a sectional view showing the rule in unfolded position. Fig. 3 is an end elevation showing 30 the rule in closed position.

Referring now to the drawings, there is shown a rule including two sections 5 and 6, having hinged members 7 and 8 respectively secured thereto. The member 7 includes 35 spaced circular ears 9 of the usual type, and the member 8 includes an ear 10 located between the ears 9, the several ears having central perforations 11 therethrough, for the reception of a pivot pin 12. The member 7 40 has a longitudinally extending recess 13 formed therein and communicating with the space between the ears 9, this recess thus receiving a portion of the ear 10. As shown, the recess 13 extends beyond the ears 9 inwardly of the section 5, and opens through the outer edge of the member 7.

A block 14 is located in the recess 13, at the inner portion thereof, and has formed integral therewith, a spring tongue 15 project- 50 ing from its inner portion and extending longitudinally of the member 7, to bear

against the periphery of the ear 10. This ear is provided with flattened peripheral portions 16, located to receive the spring tongue 15 thereagainst when the sections 5 and 6 55 are in certain positions with respect to each other, the tongue holding the sections yieldably in such position, as will be readily understood. As will be seen, the block 14 rests against the outer end of the recess 13, and is 60 confined by a plurality of transverse fasteners 17 passed therethrough, and through the member 7 to hold the block against movement, and this block has a projection 18 formed integral therewith at its outer por- 65 tion and extending longitudinally of the member 7 to close the portion of the recess 13 which lies beyond the ears 9, this projection thus preventing ingress of foreign matter to the recess, which might interfere with 70 the operation of the rule.

What is claimed is,

1. A rule including two sections, a hinge member carried by each section, ears carried by one member in spaced relation to each 75 other, said member having a recess therein communicating with the space between the ears, an ear carried by the other member and pivoted between the first named ears, a block secured within the recess, a spring 80 tongue carried by the block and engaging the second named ear, and a projection carried by the block and in spaced parallel relation with the spring tongue and arranged to close a portion of the recess. 85

2. In a hinge for rulers, the combination with a member including spaced ears, of a member having an ear pivoted between the first named ears, said first named member having a recess therein communicating with 90 the space between the ears, a block secured within the recess, a spring tongue carried by the block and engaging the second named ear, and a projection carried by the block and in spaced relation to the spring tongue 95 and arranged to close a portion of the recess.

3. In a hinge for rulers, the combination with a member including spaced ears and having a recess therein communicating with 100 the space between the ears and extending beyond said ears, of a second member having

an ear pivoted between the first named ears, and a block secured in the recess, said block having a spring tongue formed integral therewith and engaging the second named ear and 5 having a projection formed integral therewith and located to close the portion of the recess beyond the ears.

In testimony whereof I affix my signature, in presence of two witnesses.

CHARLES L. BRUSH.
